UNITED STATES PATENT OFFICE.

FREDERICK CARLISLE OWEN, OF FAYETTEVILLE, NORTH CAROLINA.

TRANSFORMER FOR ELECTRIC-ARC CUTTING AND WELDING APPARATUS.

Application filed April 15, 1926. Serial No. 102,235.

This invention relates to alternating current electric arc cutting and welding apparatus, and more particularly to a novel transformer therefor.

5 The invention has for one of its objects the provision of a transformer which shall be admitted to permit an arc which is uniform and will not burn the work to be easily maintained and which will efficiently 10 function without the aid of damping devices, rheostats, resistances and the like.

A further and important object of the invention is the provision of a transformer of the character stated wherein the induced 15 voltage per turn of the secondary winding shall be greater than the impressed voltage per turn of the primary winding, whereby to reduce to the minimum the current required for the efficient welding of any metal 20 with either a coated, covered or bare electrode.

With the foregoing and other objects in view, the nature of which will appear as the description proceeds, the invention consists 25 of the combination and arrangement of parts hereinafter fully described and claimed, and illustrated in the accompanying drawing, wherein:

Figure 1 is a diagrammatic view of an arc 30 welding apparatus embodying the transformer, and

Figures 2, 3 and 4 are similar views of slightly modified forms of the transformer.

Corresponding and like parts are referred 35 to in the following description, and designated in the several views of the accompanying drawing, by similar reference characters.

The transformer comprises a laminated 40 core 1 which is preferably though not necessarily of rectangular formation. The core 1 provides but a single metallic magnetic path, and in practice is preferably supported in a vertical position.

45 The primary circuit or winding of the transformer comprises connected coils 2, 3, 4 and 5 arranged on three adjacent legs of the core 1. The coils 2 and 3 are preferably mounted on the bottom leg and the coils 4 and 5 on the side legs of the core 1. The coils 2 and 3 are reversely arranged. Leads 6 and 7 extending from any suitable source of current supply, are connected to the terminals of the primary winding.

55 The secondary circuit of the transformer

comprises a main or voltage regulating coil 8 mounted on the bottom leg of the core 1, and an auxiliary or current regulating coil 9 mounted on the top leg of the core 1. The coils 8 and 9 are reversely wound or 60 reversely connected, so that the voltages are added when connected in series by a wire 10. The coil 9 has a greater number of turns or convolutions than the coil 8, and extending from certain turns or convolutions thereof are tap leads 11, any one of which may be connected to the electrode 12 by a lead 13. The coil 8 is to be connected to the work 14 by a lead 15.

Current flowing through the primary 70 winding causes a magnetic flux to circulate through the four legs of the core 1. The back voltage in this winding is held down to the minimum due to the fact that this winding embodies a reversely arranged coil. 75 The back voltage in the reversely arranged coil is in opposition to the corresponding voltage in the remainder of the coil, and causes a leakage of the flux for the bottom leg of the core 1 at the ends of this coil. 80 This flux leakage is particularly noticeable at the lower left hand corner of the core 1. This results in the lowering of the effective back voltage in the primary winding and a consequent higher exciting current and 85 greater flux density in the core. In other words, the effect of the reversed coil of the primary winding is a greater induced voltage per turn in the secondary winding than the impressed voltage per turn in the primary 90 winding. It will thus be apparent that the efficient welding of any metal with either a coated, covered or bare electrode is possible with the use of but a comparatively 95 small amount of current.

Practically all the flux developed by the primary winding will thread the main or voltage regulating coil 8, because of the close association of this secondary coil with the primary, and flux in this part of the core remains substantially constant at all loads. As the result the voltage generated in the secondary coil 8 likewise remains practically the same at all times, and does not vary with the load.

The auxiliary or current regulating coil 9 of the secondary winding, being remote from the primary winding, tends to set up a flux independent of and opposed to that generated by the primary winding. Owing 105

to the location of the coils, this secondary flux is confined substantially to the top leg of the core 1. The primary flux threads the bottom and side legs of the core, and also tends to permeate the top leg. In this top leg, however, it is opposed and choked back by the flux due to the secondary winding 9, and as the result there will be a certain amount of flux leakage from each end of the primary coils 4 and 5. Owing to the opposing and choking effect of the secondary coil 9, however, a very exaggerated leakage takes place at the two upper corners of the core, or, in other words, by far the greatest portion of flux is forced out of the closed metallic path into the air at these points. The larger the current drawn from the secondary winding, the greater this leakage becomes.

20 As the result of such leakage, the heavy secondary flux causes the coil 9 to develop high inductance, and act as an impedance coil, so that the phase of the voltage in this part of the secondary winding is shifted.

25 The resulting voltage at the arc is therefore reduced, or at least prevented from increasing as the current increases. The impedance action increases with the load, so that even on short circuit serves to prevent 30 an excessive or dangerous flow of current. Thus a stable arc is maintained.

In the modified form of the invention shown in Figure 2, the coils 2 and 4 are reversely arranged as are also the coils 3 and 5, and a third lead 16, extending from a source of current supply, is connected to the remote terminals of the coils 2 and 3. In this form of the invention, the entire primary winding, or only one-half thereof 40 consisting of either the coils 2 and 4 or the coils 3 and 5 may be employed. In Figure 3, the coils 2, 3, 4 and 5 are connected in parallel; that is the coils 2 and 4 and the coils 3 and 5 are paralleled. This form of 45 the invention is especially adapted for heavy welding and cutting. In the form of the invention shown in Figure 4, the primary winding consists of but two coils 2^a and 4^a reversely arranged. It is to be understood 50 that I am not to be restricted to the arrangement of the secondary coils on the top and bottom legs of the core, as such coils may be as should be apparent arranged on any two of the legs.

55 What is claimed is:—

1. A transformer having a rectangular core providing but a single metallic magnetic path, a primary winding distributed around three adjacent legs of the core and 60 having a reversed coil, and a secondary winding comprising two sections, one section being wound on the middle one of said

three legs, and the other section being wound on the opposite or fourth leg of the core.

2. A transformer having a rectangular core providing but a single metallic magnetic path, a primary winding including a reversed coil and distributed around three adjacent legs of the core, and a secondary winding comprising two coils mounted on 70 different legs of the core.

3. A transformer comprising a core providing but a single magnetic path, a primary winding embodying reversely arranged coils mounted on adjacent legs of the core, 75 a secondary coil mounted on one of said legs of the core, and a second secondary coil mounted on another leg of the core and connected to said first secondary coil.

4. A transformer comprising a core, a primary winding distributed about the major portion of the core and having a reversed coil, a secondary coil on the minor portion of the core, and a second secondary coil connected to said first secondary coil 85 and arranged on the major portion of the core.

5. A transformer comprising a core, a primary winding distributed about a portion of the core and embodying reversely 90 arranged coils, a secondary coil on said portion of the core, and a second secondary coil on another portion of the core and connected to said first secondary coil.

6. A transformer having a rectangular core, a primary winding embodying coils on the bottom leg of the core and a coil on each side leg of the core, the coils being connected, one of the coils on the bottom leg and the coil on one of the side legs being reversely arranged and the other coil on the bottom leg and the coil on the other side leg being reversely arranged, a secondary coil on one of said legs, and a second secondary coil on the fourth leg of the core and connected to 105 said first secondary coil.

7. A transformer having a rectangular core, a primary winding embodying coils on the bottom leg of the core and a coil on each side leg of the core, the coils being connected, one of the coils on the bottom leg and the coil on one of the side legs being reversely arranged and the other coil on the bottom leg and the coil on the other side leg being reversely arranged, leads connected to the coils on the side legs, a third lead connected to the remote terminals of the coils on the bottom leg, a secondary coil on one of said legs of the core, and a second secondary coil on the remaining leg of the 110 core and connected to said first secondary coil.

In testimony whereof I affix my signature.
FREDERICK CARLISLE OWEN.
